Attorney

UNITED STATES PATENT OFFICE.

MICHAEL C. OHL, OF DENVER, COLORADO.

TRAFFIC SIGNAL FOR AUTOMOBILES.

Application filed March 31, 1923. Serial No. 629,076.

To all whom it may concern:

Be it known that I, MICHAEL C. OHL, a citizen of the United States, residing at Denver, in the city and county of Denver and 60 State of Colorado, have invented certain new and useful Improvements in Traffic Signals for Automobiles; and I do declare the following to be a full, clear, and exact description of the invention, such as will enable 65 others skilled in the art to which it appertains to make and use the same, reference being had to the accompanying drawings, and to the characters of reference marked thereon, which form a part of this specification. 70

This invention relates to traffic signals for automobiles.

The automobiles have become so numerous that unless some means is provided whereby 20 the driver may indicate in some simple and comprehensible way, that can readily be seen and understood by the driver of a following or approaching car, his intention to stop or to turn, accidents are liable to occur.

25 It is customary for the drivers of automobiles to indicate their intentions by extending the left arm, but this is not practical whose closed cars are employed or where the cars are enclosed with curtains, as they 30 usually are in winter and on stormy days.

I am aware that a large number of patents have been issued for signals that are intended to be applied to automobiles for the purpose of signaling the driver's intentions 35 to stop or turn. For some reason none of these signals have been adopted to any extent and very few automobiles have any signaling means.

It is essential that a signal shall be positive in its operation and that it can be controlled by means within convenient reach of the driver.

40 It is the object of this invention to produce a signal that shall be positive in its operation and which can be relied upon to perform its function without fail, and which can be cheaply made and conveniently installed.

45 I have found that the most reliable means for operating a signal is compressed air or gas, as by employing this means the necessary force can be readily obtained for moving the signals.

50 It is a further object of my invention to produce a signal that shall employ compressed air or gas and which shall be so con-

structed that the compressed gases can be obtained from the engine so as to make it unnecessary to employ a separate compressor. 60

The above and other objects, which will hereinafter appear, are attained by means of a combination of elements which I will now describe, reference for this purpose being had to the accompanying drawing in which the preferred form is shown, and in which: 65

Fig. 1 is a side elevation of an automobile equipped with my improved signal.

Fig. 2 is a rear elevation of the car shown in Fig. 1. 70

Fig. 3 is a section of the signal, taken on line 3—3, Fig. 4.

Fig. 4 is an end view of the signal shown in Fig. 3.

Fig. 5 is a side elevation of the signal 75 shown in Fig. 3, parts being broken away.

Fig. 6 is a view showing the relationship of the elements of my combination; and

Fig. 7 is an elevation of the valve control looking in the direction of the arrow 7 in 80 Fig. 6.

The same reference characters will be used to designate the same parts throughout the several views.

Numeral 1 designates an automobile of 85 any make having front fenders 2 and rear fenders 3. Secured to the top of each fender is a signal which I have indicated as a whole by reference numeral 4. I provide four signals, one on each fender, the two signals on 90 each side forming a pair which operate together. Each signal 4 consists of a cylindrical member 5 whose ends are closed with heads 6 and 7. Within the cylinder 5 is a piston 8 which is attached to a piston rod 9 which extends through the head 6 and has 95 its outer end 10 bent rearwardly and parallel with the part inside of the cylinder. A plate or target 11 is fastened to the end 10 so as to move with it. The parts just described are enclosed within a casing 12 which is secured to the cylinder by screws 13. A spring 14 connects the end of 11 with the casing 12 and is tensioned so as to normally 100 keep the parts in the full line position (Fig. 3). A nipple 15 is secured to the end of the cylinder and serves as a means for making connection with the pipes that run to the storage reservoir. When air or gas under pressure is admitted to the cylinder through 105 nipple 15 the piston will be forced outwardly against the action of the spring 14

105

110

and will carry with it the plate or target 11 on the rear side of which is painted an arrow 16 or other insignia which indicates the direction in which the car will turn. The signal on the left front fender and the right rear fender are made like the one shown in Figs. 3 to 5 and the others are reversed or what amounts to the same thing secured to the fenders with the other side down so that 10 as a matter of fact, all four of the signals are made exactly the same. A small pocket 17 is secured to one end of the front side of each signal and contains a lamp 18 that is lighted each time the signal operates and serves to 15 illuminate the plate 11 so that it may be seen in the dark. A switch 19 is provided in the lighting circuit which is opened in the daytime when the light from lamps 18 are not needed.

20 In order to obtain the necessary supply of compressed air for operating the signals, I provide a storage tank 20 which may be secured to the automobile in any convenient position. A pipe 21 extends to the engine 25 and is connected by pipes 22 to the pipes 24 which extend from the priming cups 23 to the engine. The valves 25 are located between the point where the pipes 22 are connected to pipes 24 and the priming cup. In 30 each of pipes 22 I provide a valve 26 and these valves are interconnected in such a manner that they can be simultaneously opened and closed by a movement of the rod 27, which may extend to the instrument 35 board so as to be within easy reach of the driver. I provide a check valve 28 on the end of the pipe 21 so as to prevent the gases from flowing backwards. I have shown the check valve 28 as located inside of the tank, 40 but it may be located outside if desired. I have shown pipe 21 connected to all four cylinders, but it may be sufficient to connect it to one or two. It is evident that when the engine is operating, air and gas will be 45 forced through pipes 24, 22 and 21 into tank 20 and will be prevented from flowing backwards by the check valve 28. A safety valve 29 is connected to the tank. The two signals on each side of the car are connected 50 by means of a pipe 30 which is connected by a pipe 31 with the T 32 which is connected on one side to valve 33 and on the other to valve 34. A pipe 35 connects the tank 20 with the valves 33. A pressure 55 gauge 36 is connected to pipe 35 and is preferably located on the instrument board. Valves 33 and 34 are connected by a bar 37 in such a manner that a movement of the bar will open and close the valves, the 60 relationship of the valves being such that when valve 33 is open, valve 34 will be closed and vice versa. It is now evident that if air or gas under pressure is contained in the tank 20 and that if we open valve 33 and 65 close valve 34, the air pressure will be di-

rected to the two signals on one side of the car and will move the piston outwardly to the dotted line position (Figs. 3 and 5). When the valves are operated so as to close valve 33 and open valve 34, the air will be permitted to exhaust through valve 33 and the spring 14 will pull the plate 11 back into the casing 12. It will be noticed from Fig. 6 that there are two sets of valves 33 and 34, one set controlling the signals on the right side of the car, and the other the signals on the left side of the car. The lamps 18 are supplied with current from the ignition batteries 38. A wire 39 leads from the batteries to a stationary insulated contact 40 which is located in the path of a movable contact 41, which is connected to an insulated bar 42, which is connected to valve 34 so as to move therewith. The contacts 40 and 41 are so related to the valve 34 that they will close the circuit when the valve 34 is closed, and open it when the valve 33 is closed. In this manner the lamps 18 will always be lighted when the signal operates, providing switch 19 is closed. The valves 33 and 34 are located in such a place that the handle 43 is conveniently accessible to the driver. Although I have shown the control switch connected to the valve 34, it may be operated by any other part that moves when the signals operate.

The operation of my device is as follows: When the engine is started, the driver opens the valves 26 and keeps the same open until the gauge 36 indicates the proper pressure, after which the valves 26 are closed. When the driver desires to turn to the left, he grasps the handle 43 and moves the same from its upward (dotted line position Fig. 7) to the full line position (Fig. 7). This permits compressed gas to enter the cylinder 5 and to move the signal 11 outwardly. When the turn has been completed, the valves are moved to dotted line position (Fig. 7) and this in turn closes valve 33, cutting off the supply of compressed gas and opens the valve 34 which permits the gases to exhaust from the cylinders and the spring 14 to retract the plate 11.

Having now described my invention, what I claim is:

1. An automobile traffic signal comprising, in combination, a cylinder, a piston slidably mounted therein; a piston rod connected to said piston; a plate secured to said piston rod, said plate having an insignia thereon; a casing enclosing the cylinder and plate; a spring means for normally holding the piston and plate in retracted position; a pipe connected to the cylinder, said pipe being adapted to conduct gas under pressure to the cylinder whereby the piston will be moved against the tension of the spring means so as to cause the plate to protrude from the casing;

- a source of compressed gas; means connecting said source to the pipe; a valve in said means; a second pipe connected to the first named pipe; a valve in said second pipe; and means connecting said valves in such a manner that when one valve is closed, the other will be opened.
2. An automobile traffic signal comprising, in combination, a cylinder; a piston 10 slidably mounted therein; a U-shaped piston rod, one side of said piston rod extending through one end of the cylinder and the other side extending parallel to the cylinder on the outside thereof; a plate secured to the 15 side of the piston rod that is outside of the cylinder; a casing enclosing said cylinder and plate; spring means for normally maintaining the piston and plate in retracted position; and means for moving said plate 20 and piston against the tension of the spring, said means comprising an elastic fluid under pressure.
3. An automobile traffic signal comprising, in combination, a cylinder; a piston 25 slidably mounted therein; a U-shaped piston rod, one side of said piston rod extending through one end of the cylinder and the other side extending parallel to the cylinder on the outside thereof; a plate secured to 30 the side of the piston rod that is outside of the cylinder; a casing enclosing said cylinder and plate; spring means for normally maintaining the piston and plate in retracted position; a tank adapted to contain a 35 gas under pressure; means comprising a pipe for connecting the tank to the cylinder; a valve in said pipe whereby when said valve is opened, gas under pressure will enter the cylinder and move the piston and plate; an exhaust pipe connected to said cylinder; a 40 valve in said pipe; and means connecting said valves so that they move together and so that when one opens the other closes.
4. An automobile traffic signal comprising, in combination, a cylinder; a piston 45 slidably mounted therein; a U-shaped piston rod, one side of said piston rod extending through one end of the cylinder and the other side extending parallel to the cylinder on the outside thereof; a plate secured to 50 the side of the piston rod that is outside of the cylinder; a casing enclosing said cylinder and plate; spring means for normally maintaining the piston and plate in retracted position; a tank adapted to contain a gas 55 under pressure; means for compressing gas into said tank, said means comprising an internal combustion engine; pipes connecting the combustion chambers with said tank; a check valve in the pipe which connects with the tank; a pipe extending from the tank to the cylinder; a valve in said pipe; an exhaust pipe connected with said last named pipe; and means connecting said valves, said means moving said valves 60 in unison so that when one opens the other closes.

In testimony whereof I affix my signature.

MICHAEL C. OHL.
